UNITED STATES PATENT OFFICE.

JOSEPH W. MYERS, OF JACKSON, MICHIGAN, ASSIGNOR, BY DIRECT AND MESNE ASSIGNMENTS, OF ONE-THIRD TO JOSEPH H. MYERS, OF JACKSON, MICHIGAN; ONE-THIRD TO ARTHUR J. TUTTLE, OF DETROIT, MICHIGAN; AND ONE-THIRD TO AGNES W. MYERS AND JOSEPH W. MYERS, BOTH OF JACKSON, MICHIGAN.

THERMOSTATIC APPARATUS.

Application filed December 20, 1923. Serial No. 681,751.

My invention relates to electrically heated flatirons and consists in the improvements hereinabove described and pointed out in the claims.

5 In the accompanying drawings:—

Fig. 1 is a side elevation of an iron embodying my invention.

Fig. 2 is a plan view to an enlarged scale, with the cover removed.

10 Fig. 3 is a detail plan view similar to Fig. 2, showing the parts in a different position.

Fig. 4 is a longitudinal central section.

Fig. 5 is a detail showing one of the spring 15 arms separate from the rest of the construction.

Fig. 6 is a detail plan view showing a modified construction at the end of the spring-arms.

20 Fig. 7 is a view similar to Fig. 6 showing a second modification.

Fig. 8 is a sectional detail view the section being taken on the line VIII—VIII Figure 2.

25 Fig. 9 is a detail plan view to an enlarged scale showing the construction of the bimetallic thermostatic arms.

30 *a*, is the body of the iron, and *b* the handle—*a*², is the sole plate, and *a*³, a projection rising from the forward part of the plate *a*². I make the projection *a*³ of good heat conducting material such as copper and join it to the plate *a*², so that heat will readily pass from the plate to said projection, 35 or the projection may be made integral with the plate and of the same material.

40 In slots cut into the lug *a*³ from its upper end I place bimetallic thermostatic arms *c*, *c*, so that they shall extend toward the rear of the iron and slightly diverge from each other. These arms are forced tight into said slots so as to form a joint with the lug *a*³, through which heat will readily pass. Each 45 of said arms is made up of a plurality of thin bimetallic thermostatic strips, so that the relative large movement of a thin strip may be secured, while by using a number of strips *c*², *c*³, the strength of action of a thick strip is secured, *d*, *d*², are similar spring 50 arms, one of which is secured at one end to the outer end of each of the arms, *c*, *c*, and is electrically insulated therefrom and forms an extension thereof. *e*, *e*², are electrical

conductors by which an electric current is conveyed to and away from the arms *d*, *d*². 55 Rods *r*, *r*², are secured to the outer ends of said arms and extend toward each other and are provided with contact pieces *d*^a, *d*^{2a}, at their adjacent and contiguous ends.

Under normal conditions the arms *d*, *d*², 60 press the points *d*^a, *d*^{2a} into contact with a yielding pressure owing to the elasticity of said arms, but should the iron become too hot the thermostatic arms *c*, *c* would be caused to diverge by the heat imparted to 65 them which would force the arms *d*, *d*², apart and separate the contact points *d*^a, *d*^{2a}, whereby the heating circuit of the iron would be broken.

f, is an elastic arm connected at one end 70 to the arm *d* and connected arm *c*, extending toward the rear of the iron and diverging toward the arm *d*²; *f*², is an arm similar to the arm *f*, but secured to the arm *d*².

g, is a rod bearing in, and extending 75 through, the upper horizontal wall of the cover of the iron and adapted to be turned about its axis in said bearing. *g*², *g*³, is a double cam secured to the lower end of the rod *g*, between the arms *f*, *f*² and adapted to 80 engage against said arms to force them apart when the rod *g* is turned. *g*⁴, is a thumb-piece on the upper end of the rod *g* by which said rod may be manipulated.

The thumb-piece *g*⁴, is located beneath the 85 center of the handle *b*, and is provided with a pointer *g*⁵ which moves over a scale *g*⁶. By turning the rod *g* to a greater or less extent the cams *g*², *g*³, are made to develop the elasticity of the arms *f*, *f*² to a greater or less 90 extent which counteracts the elastic force with which the arms *d*, *d*², press the points *d*^a, *d*^{2a}, together. Thus by turning the thumb-piece *g*⁴, the elastic force that it is necessary for the thermostatic arms *c*, *c*, to 95 exert to break the circuit may be regulated and consequently the temperature at which the heating circuit is automatically broken may be selected.

Sometimes the points *d*^a, *d*^{2a}, will stick 100 together at some points of their contiguous surfaces. When the arms *d*, *d*², are acted upon by the arms *c*, *c*, the curvature of the arms *d*, *d*², is altered because of their elasticity which rocks the surfaces of the contacts *d*^a, *d*^{2a}, upon each other, thus prying 105

the sticking points of said surfaces apart. To increase this rocking action the arms d , d^2 , are made smaller at their ends adjacent to the contact points as shown for example, 5 from d^3 to d^4 in Figure 5.

It is desirable to have the points d^a , d^{2a} , 10 separate positively, surely and quickly. To accomplish this object I provide an automatically operated mechanical means, supported by the arms d , d^2 , at their outer ends 15 for causing the prompt and certain separating of said points. This is described as follows:

h , is a metal strip secured to, but insulated from the rod r , h^2 , is a similar strip similarly secured to the rod r^2 . The strips h , h^2 are bent inward as shown and their free ends are formed to present hollow grooves toward each other and approximately 20 in a vertical plane through the longitudinal axis of the iron, into which grooves the ends of the plate j are placed. The strips h , h^2 are so shaped and located that they develop an elastic force in the arms d , d^2 , 25 pressing against the ends of the plate j . Under normal operative conditions the plate j is located as shown in Figure 2, so inclined to the forces upon its ends that it tends to force the points d^a , d^{2a} , closer together. When the working temperature of 30 the iron is exceeded the arms d , d^2 , are flexed so as to carry the ends of the plate j , by the line of the forces on its ends, as shown in Figure 3, and this plate then acts 35 to force the points d^a , d^{2a} , quickly and certainly apart.

Instead of utilizing the elasticity of the arms d , d^2 , to act upon the plate j , as above described, the strips h^a , h^{2a} , of Figure 6 may 40 be used which are themselves elastic.

A third construction is shown in Figure 7, in which the plate j is extended backward in a part j^a , and the contact point d^a , is placed 45 on the rear end of said extension to engage with the contact point d^{2a} located at a little distance from the outer end of the arm d^2 . The ends of the arms d and d^2 are here bent toward each other and provided with 50 grooves to engage the ends of the plate j , and bring a pressure on its ends for the purpose described.

I provide a switch in the handle of the iron by which the heating current may be turned on or shut off at the will of the operator. 55

b^4 , is a contact switch of suitable construction located in the handle of the iron and interposed in the heating circuit b^2 , is a rod 60 extending vertically through apertures in one end of the handle b , one of its ends appearing below the handle and the other above the same. The rod b^2 is connected within the handle and intermediate the ends 65 of said rod with one arm of the switch b^4 . The word "On" is placed at the upper end

of said rod, and the word "Off" at the lower end thereof. When the rod b^2 is at the lower end of its travel the switch b^4 has interrupted the circuit and the word "Off" is displayed conspicuously to view. When said rod is at the other end of its travel, the switch b^4 , has completed the circuit and the word "On" appears above the handle— b^{2a} and b^{2b} are notches in the side of the rod b^2 . b^3 is a piece of spring steel bent in the form 70 shown and presenting at proper points the salient loops b^{3a} and b^{3b} adapted to engage in the notches b^{2a} and b^{2b} . When the rod b^2 is at the upper end of its travel the loop b^{3a} engages in the notch b^{2a} and holds said 75 rod in position. When the rod is pressed down the loop b^{3b} engages in the notch b^{2b} and holds the rod in this position.

What I claim is:

1. In a thermostatic switch with two co-operating electrical contacts, two mutually opposing resilient arms in cooperative relation to each other and said contacts, means permanently connected to each of said arms and acting between said arms to control the motion thereof and accelerate the same adjacent to the contact position.

2. In an electric iron having a cover and having a thermostat adapted to regulate the temperature of the iron, a vertical rod projecting through the cover of said iron and carried by said cover, said rod being adapted to be turned from without the iron, a cam carried by said rod on the inside of said cover adapted to engage a temperature regulating member of said thermostat in such a manner as to actuate said regulating member upon rotation of said rod, said thermostat being wholly fixed to said iron and said rod being removable with said cover.

3. In a switch the combination of two movable arms carrying contacts, one of said arms being flexible, a part permanently connected to each of said arms lying approximately parallel to said flexible arm and pivotally engaging one of said arms at a point at one side of its axis at one end and being pivotally engaged at the other end so that said arm is bent by the action of said part and exercises because of its resilience a longitudinal force upon said part, said part and said arm being so located that a movement of said arm shall carry said part over its center to secure a quick break of contact.

4. In an electric iron having a cover and having a thermostat adapted to regulate the temperature of said iron, a vertical rod projecting through the cover of said iron and carried by said cover, said rod being adapted to be turned from without the iron, said rod being adapted to engage a temperature regulating member of said thermostat in such a manner as to actuate such regulating member upon rotation of said rod, said thermostat being wholly fixed to said iron and

said rod being removable with said cover.

5. In a switch, the combination of two thermostats, a resilient extension from each of said thermostats, contacts carried by said extensions, and a snap-over member between said resilient extensions.

6. In a switch, the combination of a flexible arm carrying a contact, a second contact with which the first named contact is

adapted to coat, a thermostat adapted to 10 act upon said flexible arm and a snap-over member between said contacts adapted to be carried over its center by the flexing of said arm when acted upon by said thermostat.

In testimony whereof, I sign this specification. 15

JOSEPH W. MYERS.
